UNITED STATES PATENT OFFICE.

CHARLES H. BARR, OF LITCHFIELD, CONNECTICUT.

VACUUM CLEANER.

Application filed October 23, 1922. Serial No. 596,314.

To all whom it may concern:

Be it known that I, CHARLES H. BARR, a citizen of the United States, and a resident of Litchfield, in the county of Litchfield 5 and State of Connecticut, have invented a new and Improved Vacuum Cleaner, of which the following is a full, clear, and exact description.

This invention has relation to vacuum 10 cleaners and has to do particularly with an improvement in the construction of the intake nozzle and the manner of supporting the same from the surface to be cleaned.

In the common and accepted forms of 15 vacuum cleaners, the intake opening of the suction nozzle is supported and maintained in uniformly spaced relation to the surface to be cleaned whereby a constant suction draft is always acting on the surface. It 20 is therefore essential to adjust the spacing of the intake opening with respect to rugs or carpets of various thicknesses to obtain the maximum efficiency of the machine, and due to the fact that such adjustments 25 of necessity are very delicate, it follows that only experienced operators obtain the best results.

It is, therefore, one of the main objects 30 of the present invention to provide a vacuum cleaner which includes means for constantly maintaining the intake opening of the suction nozzle at the proper height for efficient cleaning, thereby eliminating the necessity of regulating the same to correspond to the surface to be cleaned.

As a further object the invention contemplates a vacuum cleaner which is supported from the surface to be cleaned in such a manner as to cause, during its operation, a 40 variation in the size of the intake opening in order to subject the surface being cleaned to variable impulses or accelerations in the suction.

The invention furthermore contemplates 45 a supporting means which prevents the lifting or displacement of rugs or carpets during the cleaning operation and which acts further to crimp paper to permit the suction draft to act upon the same for removing it 50 from the surface.

As a still further object the invention provides a vacuum cleaner which greatly simplifies the construction by reducing the 55 number of working parts to a minimum, due to the elimination of brushes, drive wheels,

beaters, or other elements which constitute parts of cleaners now on the market.

Furthermore the invention contemplates a simplified, efficient, fool-proof, vacuum cleaner which is more easily handled than 60 those now in general use, which accomplishes the work in a minimum of time and which facilitates the cleaning in corners and under objects.

With the above recited and other objects 65 in view, the invention resides in the novel construction set forth in the following specification, particularly pointed out in the appended claims and illustrated in the accompanying drawing, it being understood that 70 the right is reserved to embodiments other than those actually illustrated herein to the full extent indicated by the general meaning of the terms in which the claims are expressed. 75

In the drawing—

Figure 1 is a fragmentary side elevation of a vacuum cleaner constructed in accordance with the invention, parts being broken away and shown in section, and the 80 same illustrating in full and dotted lines the operating positions.

Fig. 2 is a front view thereof, parts being broken away and shown in section.

Referring to the drawing by characters 85 of reference, 10 designates the handle, 11 the motor housing, and 12 the fan case, which case and housing are rigidly supported from the handle and house a section creating means of any approved type. The 90 nozzle 13 is rigidly attached to the fan case in any desired manner and is preferably of elongated cylindrical construction having a central hollow boss 14 which connects with the fan case and establishes communication 95 between the interior of the nozzle and the fan, the greater length of said nozzle being disposed transversely to the path of travel of the cleaner. The nozzle is provided with a transversely arranged intake opening 15 on the under side and is formed with aligned bearing bosses 16 in the end walls 17 in which the opposite ends of a transverse shaft 18 are journaled. A plurality of disks 19 are secured on the shaft 18 in transversely spaced relation to constitute supports for the rods or wires 20 arranged concentric to the axle and parallel thereto to constitute in its entirety a bearing roller 100 which extends slightly beyond the outer per-

105

110

riphery of the nozzle and projects through the opening 15. In view of the fact that the rods or wires 20 are spaced from each other circumferentially the periphery or bearing surface affords openings there-through which allow at the same time for the free passage of air and dust there-through while acting to prevent the picking up of large objects which might in any way 10 tend to clog up or hinder the proper operation of the fan. In practice the lower end of the device is directly supported from the surface over which it operates by the roller thereby disposing the lips or edges which 15 define the opening 15 a given distance from the rug, carpet or other object to be cleaned and eliminating the necessity of regulating the same for various kinds of carpets, rugs, or the like. Due to the rigid connection of 20 the handle with the fan case motor housing and nozzle, the roller when the device is in operation will function as a support or mounting to permit of a longitudinal rocking of the nozzle whereby variation of the 25 size of the intake opening will be effected to subject the surface to be cleaned to variable impulses. This action has been found by actual experiment to more effectively dislodge and remove the dust, dirt, or other 30 foreign matter from the surface to be cleaned. The roller when moving will further function to throw out by a centrifugal force anything that may be picked up and cling to the inside thereof. It will be further noted that the roller prevents the lifting of the carpet or rug from the floor to any appreciable extent as the weight of the machine supported by the roller overcomes this objection. The crimped periphery or 35 bearing surface of the roller acts in the case of papers to crimp the same in order that the suction draft may properly act thereon to remove it from the surface of the rug, floor or carpet.

40 45 I claim:

1. A vacuum cleaner including a handle, a nozzle having an intake opening rigidly supported from said handle, and a supporting roller mounted within said nozzle with the periphery thereof projecting through 50 said opening in spaced relation to the side

walls of the opening whereby upon operation of the device over the surface to be cleaned a longitudinal rocking movement will be effected for varying the size of the 55 effective portion of the intake opening and imparting variable impulses to the suction draft, the periphery of said roller having openings therethrough.

2. A suction nozzle for vacuum cleaners 60 comprising a casing having an intake opening, a roller mounted for turning movement within said nozzle with the periphery thereof extending through the intake opening to constitute a support for the cleaner, said 65 roller consisting of a central shaft, circumferentially spaced rods arranged concentric to the central shaft constituting the periphery of said roller, and longitudinally spaced disks on the shaft for supporting the rods 70 therefrom, the periphery of the supporting roller being spaced from the side edges of the intake opening.

3. The combination with a vacuum cleaner including a handle and a suction 75 creating means, of a nozzle communicating with said suction creating means, said nozzle comprising a cylindrical casing having an intake opening at the lower portion of its periphery, a transverse shaft journaled 80 in said casing, a plurality of longitudinally spaced disks on said shaft and a plurality of longitudinally extending circumferentially spaced concentric rods carried by the periphery of the disks to constitute a foraminous roller, the periphery of which extends through the intake opening and projects beyond the periphery of the nozzle casing in spaced relation to the side walls of the intake opening, whereby said roller 85 serves to support the nozzle for movement on a surface which is to be cleaned in spaced relation to the surface.

4. In combination, a vacuum cleaner having a nozzle provided with an intake opening through which a suction draft moves, of a foraminous roller mounted in the nozzle and extending through the intake opening thereof for supporting the cleaner for longitudinal rocking movement upon the 100 surface to be cleaned.

CHARLES H. BARR.
